INTERNAL-COMBUSTION ENGINE

Cleveland H. Jelley, Detroit, Mich.

Application June 27, 1946, Serial No. 679,659

9 Claims. (Cl. 123—50)

1

This invention relates to internal combustion engines.

One object of this invention is to provide an internal combustion engine wherein the explosive power is applied to a pair of pistons in each cylinder moving in opposite directions, thereby requiring only half the stroke for each piston as compared with a conventional engine and also enabling the pistons and their connecting rods and other moving parts to be made with the same total weights so as to effect perfect balance of the crankshaft, pistons and connecting rods and substantially eliminate pressure or thrust on the main bearings and crankcase other than actual power torque.

Another object is to provide an internal combustion engine, as set forth in the preceding object, wherein the conventional cam shaft is eliminated entirely and each cylinder or set of cylinders, if a radial set, is provided either with a cam formed upon one cheek of the crankshaft or a cam mounted directly upon the crankshaft, the cam in either case engaging a cam follower connected to a valve which at least controls the intake of fuel and also, if desired, the exhaust of the exploded gases, as in a four-cycle engine.

Another object is to provide an internal combustion engine, as set forth in the preceding objects, which may be constructed with any desired number of cylinders and with any desired apportionment of these cylinders radially or in line, or in a plurality of sets of radial cylinders arranged in line, thereby enabling the use of an uneven number of cylinders and eliminating the synchronism of revolution and power impulses so as to result in substantially vibrationless operation.

Another object is to provide an internal combustion engine, as set forth in the object immediately preceding, wherein the crankshaft may be made much shorter than in a conventional engine and only about half the diameter thereof for the same length of stroke, and consequently also enabling a correspondingly short crankcase to be employed.

Another object is to provide an internal combustion engine as set forth in the preceding objects wherein the short throws and large diameters of the bearings capable of being used make it possible to provide an oil passageway running through the centerline of the shaft or, in the case of aircraft engines for combat duty, for providing a rifled bore through the center of the crankshaft for the firing of machine gun bullets or cannon shells.

2

Another object is to provide an internal combustion engine, as set forth in the preceding objects, wherein the outer piston is in the form of a hollow cylinder having the inner piston reciprocable therein in an opposite direction, both pistons in this dual stroke construction moving half the stroke length of a conventional engine with a single piston in each cylinder, hence requiring only half the angularity of the connecting rods and accordingly enabling the stroke to be unusually long in proportion to the bore as contrasted with the conventional engine, without unduly increasing either the angularity of the connecting rods or resulting in an excessive piston speed.

Another object is to provide an internal combustion engine, as set forth in the preceding objects, which by reason of its dual stroke construction, reduces piston slap and provides substantially perfect balance of the moving parts, hence enabling the attainment of a power curve peak considerably higher than in a conventional engine because of the lower consumption of power required to overcome the inertia of reciprocating parts and thereby enabling the attainment of more power impulses in a given period of time, so as to produce a more powerful engine than conventional engines of a given size and weight.

Another object is to provide an ignition device for internal combustion engines wherein the igniter, such as a spark plug, is brought into communication with the explosion chamber only at the instant of the explosion, thereby protecting its electrodes and enabling longer life thereof at a greater operating efficiency.

Another object is to provide an improved fuel gas distributor having a free rotating impeller which keeps the gases in motion even while the valves are closed, so that the gas is not required to start and stop its motion periodically as in the conventional engine.

Another object is to provide an internal combustion engine, as set forth in the preceding objects, wherein an auxiliary chamber is provided for receiving the incoming fuel gas and for transferring it to the explosion chamber after being pre-compressed.

Another object is to provide a four-cycle internal combustion engine of the type set forth in the preceding objects, wherein the cheeks of the crankshaft are provided with cam portions arranged side by side with a cross-over point on the same level for engagement by a laterally shiftable cam follower, such as a

roller, a valve being connected to the cam follower for reciprocation thereby.

Another object is to provide a four-cycle internal combustion engine of the type set forth in the object immediately preceding, wherein the valve consists of a hollow plunger with longitudinally spaced ports timed to communicate with intake and exhaust manifolds in a pre-ranged cycle of operations.

Another object is to provide a two-cycle internal combustion engine of the type set forth in the preceding objects, wherein there is only one cam required for each cylinder or cylinders if located radially, this cam being either formed on a cheek of the crank shaft or mounted thereon and engaging and actuating a cam follower or roller which is not required to shift laterally to operate the valve connected thereto to properly control the intake of fuel gas, the exhaust of the exploded gases being disposed of by cooperating ports in the outer piston and cylinder.

Figure 1 is a side elevation, partly in longitudinal vertical section, of a four-cycle internal combustion engine according to a preferred form of the invention, with the outer and inner pistons at the instant of commencing a compression stroke;

Figure 2 is a cross-section through the center line of the cylinders taken along the line 2—2 in Figure 1;

Four-cycle engine of present invention

Referring to the drawings in detail, Figures 1, 2 and 3 show a four-cycle engine, generally designated 10 according to a preferred form of the invention and including a generally designated crankcase assembly 11, cylinder assembly 12, valve assembly 13, crankshaft and cam assembly 14 and cam-operating assembly 15 respectively. The crankcase assembly 11 (Figure 2) preferably consists of a lower half or sump 16 having a flanged edge 17 bolted as at 18 to the lower edge 19 of the upper half 20. The crankcase assembly 11 includes partitions or bulkheads 21 in the form of webs containing bearing bosses 22 with bearing bores 23 in which are journaled the main bearing portions 24 of the crankshaft 25. The crankshaft 25 is formed with sets of crankpins for each radial group of cylinder assemblies 12 (Figure 2), each set consisting of a central crankpin 26 disposed on one side of the crankshaft center line or axis of rotation 27 and a pair of crank pins 28 on either side of the crank pin 26 and disposed on the opposite side of the center line 27 thereof, these being interconnected by crank webs 29. The crank pins 28 are also connected to the crank shaft 27 by crank webs 30.

Mounted on each crank pin 26 is the journal portion 31 of a primary master connecting rod 32. The journal portion 31 consists of upper and lower halves 33 and 34 respectively (Figure 2) bolted together as at 35, the upper half 33 being provided with radially extending lugs or ears 36 carrying pins 37 to which are connected the lower ends of subsidiary connecting rods 38. The upper ends of the connecting rods 32 and 38 are enlarged as at 39 and provided with bores 40 engaging wrist pins 41 (Figure 1) which in turn engage opposed aligned bores 42 in the internal bosses 43 of the inner pistons 44. The latter are provided with skirts 45, heads 46 and piston rings 47 and 48, the latter being as many or as few as desired.

Mounted on each of the side crank pins 28 is a similar secondary master connecting rod 49 having a journal portion 50 engaging the crank pin 28 and lugs or ears 51 (Figure 2) carrying pins 52 to which are connected subsidiary secondary connecting rods 53. The upper ends of the connecting rods 49 and 53 are enlarged as at 54 and bored as at 55 to engage pin-like lugs 56 (Figure 1) integral with and extending axially in opposite directions from the oppositely directed cross head portions 57 on the lower ends of the outer pistons 58. Threaded into the lugs 56 are retaining bolts 56a having retaining washers 51a for the connecting rods 49. The outer pistons 58 are of cylindrical form with bores 59 in which the inner pistons 44 are mounted for reciprocation. The outer pistons 58 are provided with heads 60 and side walls 61, the latter containing an ignition port 62 near the head 60 for exposing the electrodes of a spark plug at the instant of ignition, as will subsequently be described. The port 62 may be of any outline desired, being

shown for convenience as rectangular (Figure 2). The side wall 61 of the outer piston 58 is likewise provided with an elongated port 63 (Figure 1) opposite the port 62 and serving as a combined intake and exhaust port. The outer piston 58 is reciprocably mounted in a bore 64 in the inner wall 65 of the cylinder 66 of the cylinder assembly 12, this being provided with an outer wall 67 and a water jacket or chamber 68 therebetween.

The cylinder walls 65 and 67 are interconnected by a boss 69 having a threaded bore 70 for receiving a conventional spark plug 71 having electrodes 72. The inner end of the bore 70 communicates with and is exposed by the port 62 when the outer cylinder 58 is at the bottom of its down stroke in the firing position. This construction exposes the spark plug electrodes only at the instant of ignition and covers them at all other times except that the bottom of the down stroke of the exhaust stroke of the outer piston 58, thereby protecting the electrodes from fouling and corrosion and increasing their life and efficiency, particularly in aircraft engines. The spark plugs 71 are connected to a conventional ignition system including a timer and distributor operatively connected to the crankshaft 27. The details of this system form no part of the present invention and any suitable conventional system may be employed. The outer piston 58 near its head 60 is provided with one or more piston rings 73.

The cylinders 66 at their lower ends are flanged as at 74 and secured to the upper half 20 of the crank case assembly 10 by bolts 75. The upper crankcase half 20 for the three radial cylinder design shown in Figures 2 and 3 is provided with longitudinal flat wall portions 76 inclined at obtuse angles to one another (Figures 2 and 3) and provided with apertures 77 therethrough for receiving the lower portions 78 of approximately annular guide members 79 having sealing rings 80 disposed in grooves therein and engaging the outer surfaces of the outer cylinders 58. The upper portions 81 of the guide members 79 are seated in annular recesses 82 in the lower ends of the cylinders 66 and have downwardly extending guide arms 83 with inwardly facing parallel guide surfaces 84 for the reception of the crosshead portions 57 on the lower ends of the outer pistons 58. The crosshead portions 57 have parallel side walls spaced apart the same distances as the separation of the guide surfaces 84 so as to be guided thereby while reciprocating therein. This construction prevents the turning of the outer cylinders 58 while they are reciprocating, thereby preserving the proper alignment of the ports 63.

The outer cylinder 58 at the upper end of its stroke has its head 60 spaced apart from the corresponding head 85 of the cylinder 66 so as to provide a pre-compression chamber 86 therein having a port 87 in the side wall thereof opening into a passageway 88 leading to a port 89 in a cylindrical valve bore 90. Similarly, the port 63 opens into a port 91 and passageway 92 leading to a port 93 in the valve bore 90. The outer and inner pistons 44 reciprocate toward and away from one another so as to provide an explosion chamber or main chamber 94 between the opposing heads 46 and 60 adapted to communicate through the port 87 with the pre-compression chamber 86 when the outer cylinder 58 is at the top of its stroke (Figure 1).

Reciprocably mounted in the valve bore 90 is a tubular valve member 95 having upper and

lower transverse partitions or bulkheads 96 and 97, the partition 96 forming with the side walls 98 thereof an exhaust chamber 99. The latter is provided in one wall portion with a port 100 adapted to register with the port 93 and in its opposite wall portion with a port 101 adapted to register with a port 102 leading to the exhaust passageway 103 in the exhaust manifold 104, the latter being bolted as at 105 to the valve housing portion 106 projecting laterally from the cylinder 66 and forming a part of the valve assembly 13. The upper chamber or intake chamber 107 of the valve member 95 is provided with a port 108 in the side wall 98 above the partition 96 and adapted to register with the port 89. The upper end of the valve member 95 is provided with an internal bore 109 engaging the outer wall of a tubular member 110 having a flanged upper end 111 seated in an annular recess 112 in the upper end of the valve bore 90. A coil spring 113 is mounted in the space between the tubular member 110 and the valve bore 90 with its upper end engaging the flanged portion 110 and its lower end engaging the top 114 of the valve member 95 so as to urge the latter downwardly therein. The coil spring 113 is thus completely enclosed so that in the event of accidental breakage, its parts cannot escape into other portions of the engine and cause damage. The tubular member 110 is held in position by the lower end flange 115 of the intake manifold 116 which is bolted as at 117 (Figure 3) to the top 118 of the valve housing portion 106.

The side wall 98 of the tubular valve member 95 is provided immediately beneath the lower partition 97 with oppositely disposed elongated slots 119 through which extends a bridge member 120 having ports 121 therein. The bridge member 120 serves as an abutment for the upper end of a coil spring 122 and also to prevent rotation of the valve member 95. The lower end of the coil spring 122 engages the shouldered portion 119a below the slots 119 and urges the valve member 95 downwardly. The outer ends of 45 the bridge member 120 rest upon the surfaces 76 of the upper crankcase halves 20 and are received in recesses 123 in the lower ends of the valve housing portions 106 (Figure 1).

The upper crankcase half 20 is provided with 50 bores 124 aligned with and of the same diameter as the valve bores 90 so as to form, in effect, continuations thereof for reciprocably receiving the tubular valve members 95. The lower end of each valve member 95 is provided with downwardly directed arms 125 having aligned transverse bores 126 in which are mounted the opposite ends of an axle 127 carrying a roller or cam follower 128 which is loosely rotatable and slideable thereon. The roller 128 is provided with 55 a hub 129 having an annular groove 130 for receiving the opposite ends of a shifting yoke 131 of hollow rectangular construction (Figures 1, 5 and 6) which in turn has an arm portion 132 extending through a rectangular aperture 133 in the crankcase web 21. The arm portion 132 terminates in a slide block 134 of approximately rectangular outline mounted for horizontal reciprocation in a guideway or groove 135 formed in a guide bracket 136 (Figure 4) having a flange 137 bolted as at 138 to the underside of the upper crankcase half 20. The guide groove 135 is partially closed by a plate 139 bolted as at 140 to the bracket 136 and having a bore 141 therein for receiving one end of a shaft 142. The slide block 134 is provided with an approximately ellip-

tical opening 143 having arcuate portions 144 engaged by the opposite ends of a rotating arm 145 forming a part of the shaft 142. Beyond the arm 145, the shaft 142 passes through and is journaled in a bore 146 in the bracket 136 and has secured to its opposite end as at 147 the hub of a spiral worm gear 148. The latter meshes with a spiral worm 149 mounted on and driven by the crank-shaft 25. The worm 149 and worm gear 148 are so proportioned that when the crankshaft 25 rotates, the driving connection formed by the spiral worm 149 and worm gear 148 causes the shaft 142 to rotate at half the speed of the crank-shaft 25, thereby rotating the arm 145. As the latter rotates, it alternately engages the arcuate portions 144 of the opening 143, causing the slide block 134 to reciprocate, thereby shifting the cam follower or roller 128 intermittently to and fro along its axle 128.

The cam follower or roller 128 engages a dual cam 150 (Figures 11 and 12) having cam paths 151 and 152 side by side and provided with a bore 153 and a keyway 154 by which it is keyed as at 155 to the crankshaft 25. The cam path 151 is provided with a circular dwell portion 156 passing through a cross-over portion 157 to a raised exhaust operating portion 158 of larger diameter than the dwell portion 156. On the other hand, the cam path 152 is provided with a dwell portion 159 connected with the cross-over portion 157 and of the same diameter as the dwell portion 156. The dwell portion 159 is connected to an intake operating portion 160 which is of smaller diameter than the dwell portions 156 and 159. The proportionate lengths and heights of the various cam portions will, of course, depend on the particular design of engine. In one design, for example, the portions 158 and 160 were provided with a one-half inch rise and fall respectively, with a dwell of approximately 150 degrees, thereby providing a transition or blend of about 30 degrees from rise or fall. The shift of the cam follower or roller 128 takes place of course at the cross-over point 157.

Rotary fuel distributor

In the conventional internal combustion engine, the problem of the proper fuel distribution has been a serious one, due to the fact that the fuel gas starts and stops motion every time one of the intake valves opens and closes. This starting and stopping of the motion of the gas many times a second prevents the highest efficiency being obtained in an engine, particularly at higher speeds.

In order to overcome this problem, the present invention provides a rotary fuel distributor generally designated 161 (Figures 23 and 24) whereby the fuel gas is maintained continuously in motion while the engine is running, regardless of the opening and closing of the intake valves. This rotary fuel distributor 161 may be used either with the two-cycle or four-cycle type of engine, and is especially useful in the two-cycle type. The rotary fuel distributor 161 consists of a generally circular casing 162 having upper and lower halves 163 and 164 bolted together as at 165. The casing 162 is provided with a hollow annular peripheral chamber 166 formed between the oppositely curved portions 167 and 168 of the upper and lower casing halves 163 and 164. Arranged at intervals around the periphery of the curved portion 168 of the lower casing half 164 and opening into the chamber 166 are ports 169 (Figure 23) to which the intake mani-

8
folds 116 are connected. The intake manifolds 116 are positioned to lead tangentially away from the casing chamber 166 so as to enhance the flow of fuel gas thereto from said chamber 166.

5 The lower casing half 164 is provided with a central boss 170 having a socket or recess 171 in which is journaled a shaft 172 freely rotatable therein. The shaft 172 is shown, for purposes of simplicity, as having plain bearings whereas in actual practice conventional anti-friction bearings would be used. The shaft 172 is also shown as provided with an annular shoulder 173 forming a thrust surface, whereas in actual practice an anti-friction thrust bearing of a conventional type would be used. Such bearings are commercially available and their details form no part of the present invention. Mounted on the upper end of the shaft 172 is an impeller or rotor 174 having a socket 175 in the center thereof for receiving the shaft 172. The rotor 174 consists of a hub 176 having spiral vanes 177 radiating outwardly therefrom and terminating in enlarged approximately circular end portions 178. The upper casing half 163 is provided with a central 10 axial conduit portion 179 having a flange 180 with bolt holes 181 for attachment to the main intake manifold leading thereto from a conventional carburetor (not shown).

20 The rotor 174 is thus freely rotatable in its bearing recess 171, rotation being accomplished by the suction produced in the various intake manifolds 116 through the ports 169, each giving an impulse to the vanes 177 and their end portions 178. The momentum of the rotor 174 tends 25 to keep it in rotation like a fly-wheel even when the individual intake valves of the cylinders 88 are closed, so that only the portion of the fuel gas in the various intake manifolds 116 halts momentarily such valves are closed. The main body of the gas is impelled to move in an orbital path around the chamber 166 until each intake valve opens and sucks in a charge of fuel gas. The rotary fuel distributor 161 thus has a cyclonic 30 action which applies a slight pressure to the gases, keeps them agitated and free from recondensation and counteracts the inertia so prevalent in conventional manifolds. The intake manifolds 116 are, so far as possible, made of 35 the same lengths and diameters so as to have approximately the same volumes, and the most 40 efficient gas distribution occurs when the cluster arrangement of the present invention is employed, with the cylinder assemblies 12 partially radial and partially in line.

Operation of four-cycle type of engine

In the operation of the four-cycle type of engine, according to the invention (Figures 1 to 16 inclusive), let it be assumed that the moving parts of the engine are in the positions shown in Figures 1 and 13 with the outer and inner cylinders 58 and 44 at dead center in their positions of greatest separation, having drawn in a charge of fuel gas into the explosion chamber 94 between them. It will be further assumed that a portion of fuel gas has been previously drawn into the pre-compression chamber 86 between the top of the outer piston 58 and the cylinder head 85, as will be subsequently described in connection with Figure 15. The outward motion of the outer piston 58 has compressed this charge in the pre-compression chamber 86 and when the outer piston 58 reaches its outermost position (Figure 70 13), the upper end of the port 83 communication with the next

precompressed portion of gas to move into the explosion chamber 94. The outer and inner pistons 58 and 44 are thus now at the instant of commencing their compression stroke, as shown in Figure 13, with the tubular valve 95 in a position closing all of its ports, as controlled by the position of the cam follower 128 upon the cam path 152 at the instant it is entering upon the compression dwell portion 159 (Figure 11).

As the outer and inner pistons 58 and 44 move toward one another, the cam follower 128 rolls along the compression dwell portion 159 and maintains the valve ports in a closed position while the fuel gas charge is thus compressed. As the outer piston 58 moves inward, the port 62 uncovers the bore 70 containing the spark plug 71 with its electrode 72. When the outer and inner pistons 58 and 44 reach their points of nearest approach (Figure 14), the spark timing mechanism causes a spark to pass between the spark plug electrodes 72, igniting the compressed fuel gas charge.

The explosion then occurs, causing the outer and inner pistons 58 and 44 to move away from one another, covering up the bore 70 with the spark plug electrodes 72 and protecting them from the heat and products of combustion. The pistons move apart to their points of greatest separation, transmitting the power thus generated to the crankshaft 25 through the connecting rods 32 and 49 and the crank pins 26 and 28. Since the collective weights of these reciprocating parts are substantially the same, they counter-balance one another and hence reduce vibration and bearing pressures to a minimum as compared with conventional engines. Meanwhile, the cam roller 128 has reached the cross-over point 157 (Figures 11 and 12) and has been shifted over to the cam path 151 by the rotating arm 145 acting upon the slide block 134 (Figures 5 and 6) so that the roller 128 during the explosion stroke traverses the explosion dwell portion 156, thereby keeping the valve ports closed.

When the outer and inner pistons 58 and 44 reach their points of farthest separation during the explosion stroke (Figure 15), the roller 128 climbs from the explosion dwell portion 156 to the exhaust dwell portion 158 of the cam path 151, shifting the tubular valve member 95 upward and causing the exhaust ports 100 and 101 to communicate with the exhaust ports 93 and 102 respectively and interconnect them. At the same time, the intake ports 90 and 89 are also brought into communication, and the moving parts reach the position shown in Figure 15 at the instant of the commencement of the exhaust stroke.

During the exhaust stroke, the cam follower or roller 128 traverses the exhaust dwell portion 158 of the cam path 151 while the outer and inner pistons 58 and 44 move toward one another (Figure 15), forcing the burnt gases outward in the direction of the arrows into the exhaust manifold 104 by way of the valve chamber 99. At the same time, the inward motion of the outer piston 58 enlarges the precompression chamber 86, causing a charge of fuel gas to be drawn through the intake manifold 116, tubular member 109, ports 90 and 89, passageway 88 and port 87, into the precompression chamber 86, the port 63 having meanwhile been disconnected from communication with the port 87 by reason of the inward motion of the outer piston 58.

The moving parts have now reached the instant of beginning the intake stroke in the explosion chamber 94 and the pre-compression

stroke in the pre-compression chamber 86, as shown in Figure 16. The cam roller 128 meanwhile descends from the exhaust dwell portion 158 of the cam path 151 (Figure 11), and enters the cross-over portion 157 at which point it is shifted over to the cam path 152 by the action of the cam-operating assembly 15 through the action of the rotating arm 145 upon the slide block 134. Immediately thereafter, the cam roller 128 descends to the intake dwell portion 160, shifting the tubular valve member 95 downwardly so that the intake port 90 therein is brought into communication with the port 93 (Figure 1) while the port 63 is brought into communication with the port 63.

The outer and inner pistons 58 and 44 now move away from one another from the positions of Figure 16 toward the positions of Figure 13 with the previously mentioned ports remaining open but with the precompression chamber 86 closed off. The head 60 of the outer piston 58 in moving outward, precompresses the charge of gas in the precompression chamber 86 and at the same time, the suction created by the motion of the pistons 58 and 44 away from one another, sucks in a charge of gas into the explosion chamber 94 as shown by the arrows in Figure 16. As the pistons 58 and 44 near their points of farthest separation (Figure 13), the cam follower or roller 128 reaches the end of the intake dwell portion 160 on the cam path 152 and ascends the incline to the compression dwell portion 159 thereof (Figure 11), shifting the tubular valve member 95 into the position of Figures 1 and 13 and the compression stroke begins, repeating the foregoing cycle of operation indefinitely as long as the engine is in operation.

The provision of the pre-compression chamber 86 results in a supercharge of gas therein which is transferred to the explosion chamber 94 in the manner previously described in connection with Figure 13, where it is compressed and fired along with the regular intake charge. This overcharge amounts to about 60 per cent overcharge which corresponds approximately to a maximum supercharge pressure of approximately seven pounds per square inch by conventional methods of supercharging. The pre-compression in the pre-compression chamber 86, however, is relatively slight because the outer piston 58 travels only a short distance before the ports 87 and 63 are brought into communication to transfer the pre-compressed charge from the pre-compression chamber 86 to the explosion chamber 94. This pre-compression feature provides an improved idling action, also improves performance at low speed and on grades, as well as supplying a superior getaway power.

The nine cylinder four-cycle engine shown having three cylinders radial and three in line provides 4½ power strokes per revolution. The engine shown has a three-double-throw crankshaft with the throws located 120 degrees apart and with four main bearings. The four main bearings are provided to avoid cam thrusts setting up whip in the crankshaft although only two main bearings might be sufficient in smaller engines, as the crankshaft is shorter and more rugged than in conventional engines and the stresses on the main bearings are inherently balanced by the construction and arrangement of the moving parts of the engine.

The cylinder assemblies 12 are shown as individual for purposes of clarity, but obviously they could be cast en bloc in groups of three and, in

Very small automobile engines, could be cast integral with the upper half 20 of the crankcase 10, utilizing a cradle fixture for machining. Control of speed is effected by the usual throttle, and the provision of the pre-compression charge in the pre-compression chamber 86 to the combustion or explosion chamber 94 tends to prevent recondensation and thus results in a good idling performance and in a quick start from a cold engine. Idling performance is further improved over conventional engines, by the fact that there is no overlap of valve opening in the engine of the present invention as in conventional high speed engines, the latter of which show poorer idling performance in comparison with older slower-speed engines since in conventional engines it is impossible to trim the valves properly for good performance at both high and low speeds.

The tubular valve member 85 has the exhaust ports 100 and 101 located near the lower end thereof where the coolant in the water jacket 68 is of a relatively low temperature. The construction of the valve assembly 13 and its actuating mechanism 16 and cam mechanism 14 results in the important feature that the valve member 85 is never in motion when there is pressure against it, as is the case with other reciprocating valve engines. This feature and the absence of piston thrust provides a mechanism of exceptionally long life.

Since the maximum heat of combustion occurs in the mid-portion of the cylinder 66 instead of at the top thereof, the proper circulation of the coolant in the water jacket 68 is facilitated. The shortness of the connecting rods 49, due to the short lengths of travel of the outer pistons 58 and the fact that the short rods are under tension instead of compression stress for the most part, except for the slight compression stress introduced during the precompression stroke of the outer piston 58, likewise results in improved performance and decreased vibration. Furthermore, while the individual strokes of the outer and inner pistons 58 and 44 are short, the combustion or explosion chamber 94 may be made relatively long in proportion to the diameter thereof, thus giving the improved economy of a long stroke four-cycle engine without incurring the mechanical disadvantages thereof.

The present type of engine has been illustrated in connection with spark ignition. It will be obvious, however, that compression ignition may also be employed, such as in the Diesel type of engine cycle, in which case the spark plug 71, bore 70 and port 62 would, of course, be omitted. In either event, the two pairs of rings 47 and 80 prevent loss of compression and also prevent escape of gas into the crankcase. The piston head 60 of the outer piston 58 is cooled by the intake charge of relatively cool fuel gas entering the precompression chamber 86 through the port 87, and hence its operating temperature is not harmfully greater than that of a piston head in the conventional engine. The firing order of the cylinders 66, numbered from front to back and left to right is preferably 1-5-9-3-4-8-2-6-7 as shown by the numerals on the cylinder heads in Figure 23. This firing order, however, is purely by way of illustration and not by limitation. Either the four cycle type or the two-cycle type of the present engine described below can be constructed in multiples of three cylinders from three to twenty-four cylinders and the timing works out especially well for a twelve-cylinder aircraft engine of flat or wing type having two rows of

cylinders on opposite sides with the cylinders spaced 30 degrees, three in line. Such an engine can be either in the four-cycle or two-cycle type, but with different firing orders.

Two cycle engine of present invention

The two-cycle engine of the present invention shown in Figures 17 to 22 inclusive is generally similar in construction to the four-cycle type of engine shown in Figures 1 to 16 inclusive, particularly as regards the crankshaft, connecting rod and outer and inner piston construction, and similar parts are similarly designated. The cylinder 66 of the two-cycle form, however, for convenience is provided with a removable cylinder head 200 secured to the remainder thereof by the bolts 201. The cylinder wall 65 at its upper end is also provided with an outwardly extending portion 202 containing an annular recess 203 in which is mounted a channel-shaped port ring 204 with side flanges 205 and a central connecting portion 206 having elongated inclined intake transfer ports 207 spaced at intervals therearound. Communicating with the ports 207 at the upper end of the stroke of the outer piston 58 are circumferentially spaced intake ports 208 extending through the side walls 61 thereof into the combustion or explosion chamber 94. The upper end of the outer piston 58 is also provided with piston rings 209 to seal the upper end thereof against the cylinder bore 64 in the cylinder 66.

The intermediate portion of the outer piston 58 is provided with inclined elongated exhaust ports 210 spaced at intervals therearound and communicating with an annular exhaust passageway 211 leading to an exhaust port 212 which in turn is connected to the exhaust manifold 104, not shown in Figure 17.

The two cycle engine of Figures 17 to 22 inclusive has a single path cam 213 instead of the dual path cam 158 of the four-cycle form, and is keyed or otherwise secured to the crankshaft 25. The cam is provided with a low dwell portion 214 and inclined portions 215 and 216 leading to a high dwell portion 217 (Figure 22). A cam follower or cam roller 218 engages the cam 213 and is rotatably mounted upon an axle 219 mounted in transverse bores 220 in the inwardly extending bosses 221 at the lower end of a tubular valve member 222. The latter corresponds to the tubular valve member 85 of the four-cycle form but is simplified since it is free from the ports and chambers of that form. The valve member 222 is provided with elongated slots 223 through 55 which passes a bridge member 224 with ports 225 therein and having its ends mounted in recesses 226 in a manner similar to the mounting of the bridge member 120, and serving part of the function of the latter in preventing rotation of the valve member 222.

The lower portion of the valve member 222 reciprocates in aligned bores 227 and 228 in the upper crankcase half 28 and valve housing portion 229 respectively, and at its intermediate portion is provided with an upwardly extending reduced diameter portion 230 connected thereto by an annular wall 231 and terminating at its upper end in a top portion 232. The bore 228 is continued upwardly to an annular shoulder 233 which serves as an abutment for the upper end of the coil spring 234, the lower end of which engages the annular shoulder 231 and urges the valve member 222 downwardly, retaining the cam roller 218 in contact with the cam 213. The top surface 235 of the top wall 232 cooperates with

the port 89 to control the intake of gas to the intake manifold 116, to a conventional carburetor, preferably by way of the rotary fuel distributor 161 shown in Figures 23 and 24 and previously described. An additional piston ring 236 is placed immediately below the intake ports 208 and spark plug uncovering port 236 to seal off the same.

The rotary fuel distributor 161 performs the same purpose in the two-cycle engine of Figures 17 to 22 inclusive as in the four cycle engine of Figures 1 to 16 inclusive and has the same advantages. In a two cycle nine cylinder engine of which Figure 17 shows one cylinder and which is arranged in the same manner as the four cycle engine with three cylinders in line and three cylinders radial, there are nine intake impulses of gas per revolution so that several pistons are at maximum velocity while the intake of any one cylinder is completing the cycle. The rotor or impeller 174 is thus effectively kept in motion and thus imparts a slight supercharge even though the rotor 174 is not power driven mechanically. In the two cycle engine of Figures 17 to 22 inclusive, moreover, the entire intake charge of fuel gas is pre-compressed in the pre-compression chamber 86, instead of only a portion thereof, as in the four-cycle engine.

As in the four-cycle type of engine, the two cycle type may be constructed in multiples of three cylinders, from 3 to 24 cylinders and similar considerations apply as previously described in connection with the four-cycle type of engine. The firing order for the two-cycle engine may be 1-6-5-4-9-8-7-3-2, with the cylinders numbered the same as in the four-cycle type of engine, as shown in Figure 23. The locations of the crank throws and cylinders are the same as in the four cycle type of engine.

Operation of two-cycle type of engine

In the operation of the two-cycle type of engine, as shown diagrammatically in Figures 18 to 22 inclusive, let it be assumed that the moving parts are in the positions shown in Figure 18, with the outer and inner pistons 58 and 44 at their points of greatest separation at the beginning of the compression stroke immediately after exhaust has taken place. At this point, the residual portion of the exhaust of burnt gasses is passing out through the exhaust ports 210 and 212 into the exhaust manifold while in the upper part of the outer piston 58, the incoming charge of precompressed fuel gas is passing from the pre-compression chamber 86 through the ports 207 and 208 into the combustion or explosion chamber 94. Meanwhile, the cam roller 218 has just passed down the incline 215 from the high dwell portion 217 to the low dwell portion 214 of the cam 213 (Figure 22), permitting the valve member 222 and its top surface 235 to move downwardly, opening up the intake port 89 into communication with the intake manifold 116. As the outer and inner pistons 58 and 44 move toward one another through the first quarter revolution of the crank-shaft 25, the intake and exhaust ports 208 and 210 are cut off from communication respectively with the intake transfer ports 207 and exhaust passageway and port 211 and 212 respectively. As the pistons 58 and 44 move together in this manner (Figure 19), the suction produced in the upper pre-compression chamber 86, assisted by the rotary fuel distributor 161, draws in a charge of fuel gas into the chamber 86 as shown by the arrows.

As the crankshaft rotates from the quarter revolution position of Figure 19 to the half revolution position of Figure 20, the full charge of fuel gas is drawn into the precompression chamber 86 while the fuel gas charge in the combustion or explosion chamber 94 is compressed fully. When the outer and inner pistons 58 and 44 reach their points of nearest approach (Figure 20), the port 62 opens up the bore 70 containing the spark plug 71 and at the same time, the spark timing mechanism causes a spark to jump between the electrodes 72 thereof, firing the explosive charge. Meanwhile, the cam roller 218, which has been traversing the low dwell portion 214 of the cam 213 has reached the end thereof and has passed up the incline 216 to the high dwell portion 217 (Figure 22). This action shifts the tubular valve member 222 upward to close off the intake port 89 from the exhaust manifold 116.

After the explosion takes place, the outer and inner pistons 58 and 44 move rapidly apart, compressing the charge in the pre-compression chamber 86 and expanding the charge in the combustion or explosion chamber 94, the parts being in the positions shown in Figure 21 at the instant a three-quarter revolution is reached. The outer and inner pistons continue to separate until the travel of the inner piston 44 uncovers the exhaust ports 210 and connects them with the exhaust passageway 211 and exhaust port 212, whereupon the burnt gases rush out through these ports into the exhaust manifold. At the same time, the outward travel of the outer piston 58 causes the ports 208 therein to come into communication with the intake transfer ports 207, permitting the precompressed charge of gas to rush into the upper part of the combustion or explosion chamber 94. The moving parts reach the positions shown in Figure 18 when the pistons 58 and 44 reach their positions of greatest separation, and the operating cycle previously described recommences and continues indefinitely as long as the engine is in operation.

It will be observed from Figures 17 and 18 that in the two-cycle engine the intake transfer ports 207 are long and narrow and are many in number so as to not only equalize wear on the piston rings 206 but also to serve as a flame trap to prevent preignition due to a lingering flame in the combustion chamber 94 or exhaust passageways 211 and 212. The other advantages of the four-cycle engine previously described are also present in the two-cycle type of engine, namely the cooling 55 of the piston head 60 of the outer piston 58 by the incoming gases as well as the warming of the latter, the protection of the spark plug electrodes 72, except at the instant of ignition, and the other advantages described above. In the two cycle 60 engine, moreover, the spark plug uncovering port 62 also serves as an intake port at the top of the stroke and tends to scavenge any oil which might otherwise accumulate in this port.

The exhaust ports 210 open up before the intake 65 ports 208 enter into communication with the intake transfer ports 207, this advance in opening corresponding to about 10 degrees of a revolution, thereby bringing about a sudden reduction of temperature and pressure in the combustion 70 chamber 94, and permitting the escape of most of the exhaust pressure during this interval. The exhaust continues to remain open about 10 degrees after the intake ports 207 close, thus permitting additional scavenging. The intake ports 75 208 open at about 23 degrees before and

after dead center, whereas the exhaust ports 210 open and close about 33 degrees before and after dead center.

While the four-cycle engine, for simplicity of illustration, has been shown with a non-removable cylinder head, it will be understood that it may, if desired, be provided with a removable cylinder head as in the two-cycle engine form. In either of the above engines, whether two-cycle or four-cycle, only a single worm for the timer and distributor and oil pump is required, since a combination drive shaft may be used. The distributor for a nine cylinder engine is of the nine lobe cam type, driven at full time for the two-cycle engine and at half time for the four-cycle engine.

While I have shown and described my invention in detail, it is to be understood that the same is to be limited only by the appended claims, for many changes may be made without departing from the spirit and scope of my invention.

What I claim is:

1. An internal combustion engine comprising a cylinder, a shaft, an outer piston reciprocable in said cylinder and having a longitudinal bore forming a combustion chamber, an inner piston reciprocable in said bore, said cylinder having a pre-compression chamber disposed outwardly of said outer cylinder, motion-converting mechanism operatively interconnecting said pistons and said shaft and arranged to convert the reciprocatory motions of said pistons into rotary motion of said shaft, a valve device operatively connected to and operable in timed relationship with said shaft, said valve device having an intake portion arranged for supplying fuel to said pre-compression chamber, said cylinder and said outer piston having cooperating intake and exhaust ports therethrough and operable in timed relationship with said shaft for transferring said fuel from said pre-compression chamber to said combustion chamber and for discharging the products of combustion of said fuel from said combustion chamber, said valve device having an exhaust portion spaced apart from said intake portion and cooperating with said exhaust port for discharging said products of combustion.

2. An internal combustion engine comprising a cylinder, a shaft, an outer piston reciprocable in said cylinder and having a longitudinal bore forming a combustion chamber, an inner piston reciprocable in said bore, said cylinder having a pre-compression chamber disposed outwardly of said outer cylinder, motion-converting mechanism operatively interconnecting said pistons and said shaft and arranged to convert the reciprocatory motions of said pistons into rotary motion of said shaft, a valve device having portions thereof arranged to control ports in said cylinder for supplying fuel to said combustion chamber and also for discharging the products of combustion of said fuel from said combustion chamber, a cam follower connected to said valve device, a cam device operatively connected to said shaft and having a plurality of adjacently disposed cam paths with portions thereof on the same level, and mechanism operable in timed relationship with said shaft for shifting said cam follower from one path to the other path.

3. An internal combustion engine comprising a cylinder, a shaft, an outer piston reciprocable in said cylinder and having a longitudinal bore forming a combustion chamber, an inner piston reciprocable in said bore, said cylinder having a pre-compression chamber disposed outwardly

of said outer cylinder, motion-converting mechanism operatively interconnecting said pistons and said shaft and arranged to convert the reciprocatory motions of said pistons into rotary motion of said shaft, a valve device having portions thereof arranged to control ports in said cylinder for supplying fuel to said combustion chamber and also for discharging the products of combustion of said fuel from said combustion chamber, 5 a cam follower connected to said valve device, a cam device operatively connected to said shaft and having a plurality of adjacently disposed cam paths with portions thereof on the same level, and mechanism operable in timed relationship with said shaft for shifting said cam follower from one path to the other path, said motion-converting mechanism including a crank portion with a cheek on said shaft, and said cam paths being disposed on said cheek.

20 4. An internal combustion engine comprising a housing, a shaft rotatably mounted in said housing, a set of cylinders mounted on said housing with their axes disposed radially of the axis of said shaft, an outer piston reciprocable in each cylinder and having a longitudinal bore forming a combustion chamber, an inner piston reciprocable in each bore, motion-converting mechanism operatively interconnecting said pistons and said shaft and arranged to convert the reciprocatory motions of said pistons into rotary motion of said shaft, a valve device having portions thereof arranged to control ports in each cylinder for supplying fuel to each combustion chamber, means operable in timed relationship with said shaft for discharging the products of combustion from each combustion chamber, a cam follower connected to each valve device, and a cam operatively connected to said shaft and engaging each cam follower of each set of cylinders.

40 5. An internal combustion engine comprising a housing, a shaft rotatably mounted in said housing, a set of cylinders mounted on said housing with their axes disposed radially of the axis of said shaft, an outer piston reciprocable in each cylinder and having a longitudinal bore forming a combustion chamber, an inner piston reciprocable in each bore, motion converting mechanism operatively interconnecting said pistons and said shaft and arranged to convert the reciprocatory motions of said pistons into rotary motion of said shaft, each cylinder having a precompression chamber disposed outwardly of said outer piston, each cylinder and each outer piston having mutually alignable intake and exhaust ports communicating with said combustion chamber and a valve device having a portion thereof arranged to control one of said ports in each cylinder for supplying fuel to each pre-compression chamber, said outer piston being operable in timed relationship with said shaft for transferring fuel from each pre-compression chamber to each combustion chamber and said valve device having another portion thereof arranged to control another of said ports in each cylinder for discharging the products of combustion from each combustion chamber.

6. An internal combustion engine comprising a housing, a shaft rotatably mounted in said housing, a set of cylinders mounted on said housing with their axes disposed radially of the axis of said shaft, an outer piston reciprocable in each cylinder and having a longitudinal bore forming a combustion chamber, an inner piston reciprocable in each bore, motion converting mechanism operatively interconnecting said pistons and said

shaft and arranged to convert the reciprocatory motions of said pistons into rotary motion of said shaft, a valve device having portions thereof arranged to control ports in each cylinder for supplying fuel to each combustion chamber, and also for discharging the products of combustion from each combustion chamber, a cam follower connected to each valve device, a cam mounted on said shaft and having a plurality of adjacently disposed cam paths with portions thereof on the same level, and mechanism operable in timed relationship with said shaft for shifting said cam follower from one path to the other path.

7. An internal combustion engine comprising a housing, a shaft rotatably mounted in said housing, a set of cylinders mounted on said housing with their axes disposed radially of the axis of said shaft, an outer piston reciprocable in each cylinder and having a longitudinal bore forming a combustion chamber, an inner piston reciprocable in each bore, motion converting mechanism operatively interconnecting said pistons and said shaft and arranged to convert the reciprocatory motions of said pistons into rotary motion of said shaft, each cylinder having a pre-compression chamber disposed outwardly of said outer piston, each cylinder and each outer piston having mutually alignable intake and exhaust ports communicating with said combustion chamber and responsive to the reciprocation of each outer piston for transferring fuel from each pre-compression chamber to each combustion chamber, a valve plunger having longitudinally-spaced intake and exhaust portions thereof arranged to control said intake and exhaust ports respectively in each cylinder for supplying fuel to each pre-compression chamber and also for discharging the products of combustion from each combustion chamber, and mechanism operable in timed relationship with said shaft for shifting said valve device.

8. An internal combustion engine comprising a shaft, a cylinder having a cylinder bore, an outer piston reciprocable in said cylinder bore and having an internal piston bore forming a combustion chamber, an inner piston reciprocable in said piston bore, motion-converting mechanism operatively interconnecting said pistons and said shaft and arranged to convert the reciprocatory motions of said pistons into rotary motion of said shaft, means operable in timed relationship with

said shaft for supplying fuel to said cylinder bore and for discharging the products of combustion therefrom, and an igniter in communication with said cylinder, said outer piston having a port opening into said combustion chamber and aligned with said igniter substantially at the top of the stroke of said inner piston, said mechanism being operable in timed relationship with said shaft for normally interrupting said communication between said igniter and said combustion chamber through said outer piston port and for establishing said communication only near the upper limit of reciprocation of said inner piston.

9. An internal combustion engine comprising a shaft, a cylinder having a cylinder bore, a piston reciprocable in said cylinder bore, motion-converting mechanism operatively interconnecting said piston and said shaft and arranged to convert the reciprocatory motions of said pistons into rotary motion of said shaft, means operable in timed relationship with said shaft for supplying fuel to said cylinder bore and for discharging the products of combustion therefrom, said cylinder having a recess opening into said bore, an igniter in said recess, a closure member normally disposed in said recess between said igniter and said cylinder bore, mechanism operably interconnecting said shaft and said closure member and responsive to the reciprocation of said piston to the approximate upper limit of its stroke for moving said closure member out of said recess whereby to momentarily expose said igniter to said bore, and means for energizing said igniter in its exposed position.
